(57) **CLAIM**

The ornamental design for a gel leash handle, as shown and described.

DESCRIPTION

FIG. 1 is a perspective view of a gel leash handle, showing our new design;

FIG. 2 is a rear view thereof;

FIG. 3 is a front view thereof;

FIG. 4 is a top view thereof;

FIG. 5 is a bottom view thereof;

FIG. 6 is a left side view thereof;

FIG. 7 is a right side view thereof; and,

FIG. 8 is a cross-sectional view thereof.

The lead line shown in broken line in FIGS. 1 and 4-8 form no part of the claimed design. In the cross sectional view of FIG. 8, a pliable material is disposable between a core member and an outer sheath of the handle. The outer sheath may be translucent or clear such that the pliable material and/or core material is visible through the sheath. A core member shown in broken line in FIGS. 1-8 form no part of the claimed design.

The leash lead shown in broken line in FIGS. 1 & 4-8 forms no part of the claimed design. The core member shown in broken line in FIGS. 1-8 also forms no part of the claimed design.
